No. 820,749.

PATENTED MAY 15, 1906.

T. L. VALERIUS.
TURBINE BOTTLE WASHER.
APPLICATION FILED DEC. 15, 1904.

UNITED STATES PATENT OFFICE.

THEODORE L. VALERIUS, OF FORT ATKINSON, WISCONSIN, ASSIGNOR TO
THE CREAMERY PACKAGE MFG. COMPANY, OF CHICAGO, ILLINOIS, A
CORPORATION OF ILLINOIS.

TURBINE BOTTLE-WASHER.

No. 820,749.

Specification of Letters Patent.

Patented May 15, 1906.

Application filed December 15, 1904. Serial No. 236,982.

To all whom it may concern:

Be it known that I, THEODORE L. VALERIUS, a citizen of the United States, residing at Fort Atkinson, Wisconsin, have invented 5 a certain new, useful, and Improved Turbine Bottle-Washer, of which the following is a full, clear, and exact description, such as will enable others skilled in the art to which it app-
10 pertains to make and use the same.
My invention relates to machines for wash-
ing bottles, and has special reference to wash-
ers of that class wherein the washer-brush is
driven by a steam-turbine. Quite a number
15 of such washers have been placed upon the
market from time to time in the hope of pro-
viding a simple self-contained washer, avoid-
ing the annoyances of a belt-drive, and secur-
ing a device that would not be detrimentally
20 or ruinously affected by the washing fluid
employed in cleaning bottles; but so far as I
am informed the manufacturers of such ma-
chines have almost without exception with-
drawn them from the market and the users
25 have discontinued the use of the machines
because of the many and serious accidents
sustained by users. When a bottle is placed
over the rapidly-rotating brush of a turbine-
washer, the speed thereof is much reduced, to
30 be greatly increased when the bottle is re-
moved. Again, these machines have been used
in direct connection with small steam-boilers,
with the result that even though the throttle-
valve of the turbine is carefully adjusted an
35 increase of boiler-pressure will cause a tre-
mendous increase in the speed of the machine.
Machines of this class, of commercial neces-
sity, cheap in construction, have not infre-
quently burst because the centrifugal force
40 developed by the rotation of the turbine-
wheel has exceeded the strength of the metal
composing it. In consequence turbine bot-
tle-washers have come to be regarded as ex-
tremely dangerous and unusable, although
45 acknowledged to be both exceptionally effi-
cient and most convenient and easy to oper-
ate.

The object of this invention is to provide a
simple, efficient, and perfectly safe turbine-
washer; and to this end my invention resides
50 in a machine that comprises a casing pro-
vided with a steam-nozzle and an exhaust in
combination with a turbine-wheel mounted
on a shaft in said casing, a brush-holder on

said shaft and a centrifugal or other rota-
tively-operated automatic brake operatively 55
interposed between the wheel and the casing
and adapted to positively and reliably pre-
vent the rotation of the wheel at more than a
given maximum speed, so that even though
the steam-throttle of the turbine is opened 60
wide and there occurs a considerable increase
of steam-pressure the wheel may not rotate
at more than a safe speed, all danger from
that source being effectually avoided; and,
further, my invention consists in various de- 65
tails of construction and in combinations of
parts, all as hereinafter described, and par-
ticularly pointed out in the claims.

My invention will be more readily under-
stood by reference to the accompanying 70
drawings, wherein like reference-numerals
indicate the same parts throughout, and in
which—

Figure 1 is a longitudinal vertical section
of a turbine bottle-washer embodying my in- 75
vention. Fig. 2 is a transverse vertical sec-
tion of the lower part of the machine on the
line 2^x 2^x of Fig. 1, showing the turbine-
wheel pockets or flights, the steam nozzle or
jet, and the exhaust cavity and opening. 80
Fig. 3 is an enlarged face view of an auto-
matic brake device of the construction which
I prefer to employ, and Fig. 4 is a sectional
view of the brake on the line 4^y 4^y of Fig. 3.

That form of my novel turbine bottle- 85
washer which is here shown is that which I
have determined by experiment to be at once
safe, reliable, efficient, and economical; but
it is to be, and from what follows will be, un-
derstood that my invention is capable of em- 90
bodyment in other forms and is not confined
to the special construction and machine here-
in illustrated.

While my invention extends to many of
the structural details, all of value, the gist 95
thereof resides in the combination of casing,
wheel, and automatic brake, which latter
when properly adjusted absolutely prevents
the attainment of a dangerous speed from
any cause whatsoever.

Referring now to the drawings, 2 repre-
sents the casing, substantially circular in
form, but having a suitable base 3. The
front end of the casing contains an opening
large enough to admit the turbine-wheel 4, 105
and said opening is closed by the circular

plate 5. The back of the casing is provided with a bearing-boss 6, and the plate 5 has a similar bearing-boss 7. The boss 6 is closed at the outer end and contains a simple thrust-bearing for the wheel-shaft 8, said bearing comprising a single ball 9 and the set-screw 10. The ball engages the set-screw and the shaft at single points. Both bosses 6 7 contain bushings 6' 7', providing neat bearings for the shaft. The inner walls of the turbine-case are provided with properly-faced surfaces 2' 5', against which the hub 4' of the wheel runs and by which longitudinal movement of the wheel is prevented. The wheel 15 is secured upon the shaft by one or more set-screws 4''. Oil-cup pipes 11 11 are provided for the shaft's bearings. The oil-cups are not shown. The periphery of the wheel 4 is serrated, as indicated in Fig. 1 and shown in 20 Fig. 2. The interior of the casing is of greater diameter than the wheel, except at one point, 3', at the bottom of the casing, where the wall of the casing stands close to the periphery of the wheel. This portion contains the steam 25 jet or nozzle 12, to which the steam-supply pipe 13 is connected.

14 represents the steam expansion and exhaust cavity in the base of the casing, and 15 is the exhaust-opening to which the exhaust-30 pipe is usually connected. When steam is admitted to the nozzle, it impinges upon the projections of the turbine-wheel and causes the same to rotate at a speed proportional to the velocity of the steam. All water of condensation collects in the pocket 14 and is discharged through the exhaust-opening.

The shaft 8 extends a considerable distance beyond the end of the bearing 7, and this end 8' of the shaft is considerably larger 40 than the remainder thereof. A hole 8^a is drilled into the large portion of the shaft. (See dotted lines, Fig. 1.) A transverse saw-cut 8^b and a longitudinal saw-cut 8^c are then made in the shaft to form a separate clamping 45 part or gib 8^d, secured by a ring 8^e, containing a set-screw 8^f. The internal diameter of the ring is greater than the diameter of the part 8', and the clamp thus constituted is adapted to receive brush stems or shafts 16 50 of different sizes. The bottle-washing brush 17 may partake of different shapes, according to the kinds of bottles that are to be washed. When the end of the brush-shaft is thrust into the opening in the turbine-shaft and the 55 set-screw tightened, the brush will be rigidly held in true alinement with the turbine-shaft.

I prefer to mount the automatic brake above referred to upon the end 8' of the shaft 8, and as the brake device must coöperate 60 with the stationary casing I at once provide a coöperating part and a housing for the brake by forming a large cylindrical boss 18 on the casing-plate 5. The internal walls 18' of the boss or sleeve are turned to the form of a true 65 cylinder that is concentric with the shaft 8.

The end of the boss is closed by a removable cap 19, secured by bayonet slots and screws 20. Within the housing thus formed and co-operating with the cylindrical surface 18' is the automatic brake illustrated in Figs. 1, 3, 70

and 4. This is a device that is operated by centrifugal force and comprises a disk 21, having a boss or sleeve 21' secured to the shaft part 8' by a set-screw 21''. Pivotedly mounted on the face of the disk are two arms 75 22 22, having weights 23 at their ends and carrying-blocks 24, of wood or like material. 25 25 are the pivots of the arms, and 26 26 are adjustable springs for opposing the outward throw of the brake-blocks 24. The springs 80 have their ends hooked upon the free ends of the arms 22 and are made adjustable by the screws and nuts 27 28, held in lugs 29 on the disk 21. Each arm is preferably provided with a thin web 23', having a curved slot 23'' 85 and held loosely against the disk by the head of the screw 30, fastened in the disk. The metal blocks or weights 23 are preferably integral with their arms 22, and the outer side of each contains a groove or channel 24', the walls 90 of which, together with screws 24'', (see dotted lines,) firmly hold the wooden brake-blocks. The heads of the screws are sunk deeply into the wooden blocks to provide for wear in said blocks. I prefer to provide the disk with 95 edge notches 21''', so that the wooden blocks 24 may be made wider than the parts 23 without interfering with the disk. The tension-springs of this brake device are so adjusted that they hold the brake-blocks out of engagement with the cylindrical walls of the boss 18 until a predetermined safe limit of speed is reached or exceeded.

When the speed of the turbine-wheel and shaft 8 becomes excessive, the centrifugal force developed in the radially-movable brake-blocks will overcome the force of the springs 26, and said blocks will be pressed against the friction-surface 18' on the casing-boss, thereby retarding and checking the speed of the turbine-wheel. It will be obvious that the braking effect of the rotating brake-blocks will be directly proportional to the tendency of the turbine-wheel to rotate at an excessive speed, and the automatic brake therefore 105 positively and reliably prevents the attainment of a dangerous speed—that is, a speed which would jeopardize the structure of the turbine-wheel. Aside from the fact that the frictional heat generated by the action of the 110 brake may become excessive, this bottle-washer may be permitted to run indefinitely without attention under any head or pressure of steam and will not become dangerous to persons working about it. It should be noted 115 that even if a tension-spring belonging to the brake should be broken breakage of the machine would not follow, as the related brake-block would operate with greater effect than before, tending to prevent the attainment of 120

125

130

135

a proper speed rather than to permit the speed to become excessive. When a bottle, such as a milk-bottle, partly filled with washing fluid is thrust upon the brush 17, the rotation of the brush may be slightly checked provided the pressure of steam is low; but when the bottle is withdrawn the automatic brake will prevent a sudden and dangerous increment of speed which might otherwise cause disaster.

It is obvious that numerous modifications of my invention, which will readily suggest themselves to one skilled in the art, may be made without departing from the spirit of the invention, and therefore I do not confine my invention to the specific constructions herein shown and described.

Having thus described my invention, I claim as new and desire to secure by Letters Patent—

1. In a turbine bottle-washer, a casing having a steam-nozzle and an exhaust-opening, in combination with a turbine-wheel in said casing, a wheel-shaft having bearings in said casing, a brush-holder on said shaft and a friction-brake arranged on said shaft and adapted to engage a part of said casing, and thereby retard the rotation of said wheel when the speed thereof equals a given number of revolutions per minute, substantially as described.

2. In a turbine bottle-washer of the class described, a casing having a suitable base, the axis of which is horizontal and which is provided with a steam-inlet nozzle and an exhaust-opening, in combination with a shaft mounted in said casing, a turbine-wheel mounted on said shaft, a brush-clamp on said shaft and a centrifugally-actuated automatic brake having its rotary part arranged for rotation with said wheel and its stationary part a part of said casing, substantially as described.

3. In a turbine bottle-washer comprising a suitable casing, in combination with a turbine-wheel, a shaft having a brush-holder, a boss on said casing and concentric with said shaft and a centrifugally-operated brake device mounted on said shaft for engagement with said boss, substantially as described.

4. In a turbine bottle-washer, a turbine-casing, a turbine wheel and shaft, said casing

having an external hollow boss or sleeve 18 that is concentric with said shaft, a disk 55 mounted on said shaft within said boss and centrifugal brake-blocks carried by said disk and adapted to be moved outwardly into engagement with said boss by the excessive speed of said wheel and shaft, substantially 60 as described.

5. In a turbine bottle-washer, a casing, shaft and wheel, in combination with a centrifugal brake device mounted on said shaft, and a boss formed integrally with said casing 65 and inclosing said device, substantially as described.

6. In a turbine bottle-washer, a casing, having a removable end and a hollow boss formed on said end, in combination with a 70 shaft mounted in said casing, concentrically with said boss, a turbine-wheel on said shaft, a centrifugal brake device mounted on the portion of said shaft that is within said boss, and removable end or cap closing the open 75 end of said hollow boss, substantially as described.

7. In a turbine bottle-washer, a casing having bearings in its sides, in combination with the turbine wheel and shaft in said 80 bearings, whereon said wheel is mounted, an external sleeve or boss on the side of said casing concentric with said shaft and centrifugal friction-blocks mounted on said shaft within said sleeve and boss adapted to frictionally engage the latter to prevent excessive rotation of said shaft, substantially as described.

8. In a turbine bottle-washer, a casing having bearings in its sides, in combination 90 with a shaft, a turbine-wheel mounted thereon, a stationary sleeve on the exterior of said casing and concentric with said shaft, a disk mounted on the shaft within said sleeve and spring - returned centrifugal brake - blocks 95 mounted on said disk for engagement with the inner surface of said sleeve, for the purpose specified.

In testimony whereof witness my hand, this 29th day of November, 1904, at Fort 100 Atkinson, Jefferson county, Wisconsin, in the presence of two witnesses.

THEODORE L. VALERIUS.
